(57) **CLAIM**

I claim the ornamental design for the pad for an exercise apparatus, as shown and described.

DESCRIPTION

FIG. 1 is a perspective view of a pad for an exercise apparatus showing my new design;

FIG. 2 is a rear view of the pad for an exercise apparatus;
FIG. 3 is a top view of the pad for an exercise apparatus;
FIG. 4 is a front view of the pad for an exercise apparatus;
and,

FIG. 5 is a side view of the pad for an exercise apparatus.
The broken line showing of the exercise apparatus in FIG. 1 is included for the purpose of illustrating environmental structure and forms no part of the claimed design.
